UNITED STATES PATENT OFFICE.

CHRISTIAN W. MEINECKE, OF JERSEY CITY, NEW JERSEY.

DESIGN FOR A TIP FOR ATOMIZERS OR SIMILAR ARTICLES.

SPECIFICATION forming part of Design No. 28,975, dated July 5, 1898.

Application filed May 19, 1898. Serial No. 681,166. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Tip for Atomizers or Similar Articles, of which the following is a specification.

This design relates to a tip for atomizers and similar articles, said tip having a fluted body portion.

The design is illustrated in the annexed drawings, in which—

Figure 1 is a side view of the tip. Fig. 2 is a sectional view of the tip. Fig. 3 is an end view of Fig. 1.

The body portion of the tip is shown comprising the front or tapering portion 12. The

body portion is shown fluted or with depressions 6. The interior of the tip has a smooth 20 hole or perforation 7 8.

The tip having the fluted tapering exterior and the smooth hole affords a striking, ornamental, and characteristic appearance.

What I claim as new, and desire to secure 25 by Letters Patent, is—

The design for a tip for atomizers and similar articles, substantially as herein shown and described.

In testimony whereof I have hereunto set 30 my hand in the presence of two subscribing witnesses.

CHRISTIAN W. MEINECKE.
